US00D395500S

United States Patent [19]
Ryder

[11] **Patent Number:** **Des. 395,500**
[45] **Date of Patent:** ****Jun. 23, 1998**

[54] **RESPIRATORY OXYGEN DILUTION VALVE**

[76] Inventor: **Steven L. Ryder**, 1334 W. Woodcrest Ave., Fullerton, Calif. 92633

[**] Term: **14 Years**

[21] Appl. No.: **49,825**

[22] Filed: **Feb. 1, 1996**

[51] **LOC (6) Cl.** **29-02**

[52] **U.S. Cl.** **D24/110.6**

[58] **Field of Search** **D24/110, 129, D24/110.6; 128/205.11, 204.25, 203.12, 203.21, 203.25, 203.14, 203.27, 204.18, 205.14**

Primary Examiner—Stella Reid

[57] **CLAIM**

The ornamental design for a respiratory oxygen dilution valve, as shown and described.

DESCRIPTION

FIG. 1 is a perspective view;
FIG. 2 is a bottom plan view;
FIG. 3 is a top plan view;
FIG. 4 is a side elevational view;
FIG. 5 is a side elevational view; opposite that shown in FIG. 4;
FIG. 6 is an end elevational view; and,
FIG. 7 is an end elevational view; opposite that shown in FIG. 6.
